US00D609091S

(12) **United States Design Patent**
Dubach

(10) **Patent No.:** **US D609,091 S**
(45) **Date of Patent:** **** Feb. 2, 2010**

(54) **CLOSING DEVICE**

(75) Inventor: **Werner F. Dubach**, Maur (CH)

(73) Assignee: **Kisling AG**, Tagelswangen (CH)

(**) Term: **14 Years**

(21) Appl. No.: **29/331,085**

(22) Filed: **Jan. 20, 2009**

(30) **Foreign Application Priority Data**

Jul. 21, 2008 (EM) 000974381-0001

(51) **LOC (9) Cl.** **09-07**

(52) **U.S. Cl.** **D9/438; D9/447; D9/453**

(58) **Field of Classification Search** D9/902, D9/763, 516, 453, 447, 438, 435, 440, 436, D9/434; D7/510, 396.2; D28/7; D24/224, D24/130, 112; D23/206; D10/101; 604/228; 222/82, 566, 539, 529, 526, 521, 478, 321.6, 222/153.13, 158; 221/63, 45; 220/716, 270; 215/257; 206/219

See application file for complete search history.

(57) **CLAIM**

The ornamental design for a closing device, as shown.

DESCRIPTION

FIG. 1 is a front view of the closing device;

FIG. 2 is a side view of the closing device;

FIG. 3 is a side view of the closing device;

FIG. 4 is a rear view of the closing device;

FIG. 5 is a top view of the closing device; and,

FIG. 6 is a perspective view of the closing device.

1 Claim, 6 Drawing Sheets

FIG. 1

FIG. 2

FIG. 3

FIG. 4

FIG. 5

FIG. 6

UNITED STATES PATENT AND TRADEMARK OFFICE
CERTIFICATE OF CORRECTION

PATENT NO. : D609,091 S
APPLICATION NO. : 29/331085
DATED : February 2, 2010
INVENTOR(S) : Werner F. Dubach

Page 1 of 1

It is certified that error appears in the above-identified patent and that said Letters Patent is hereby corrected as shown below:

Title page, item (30) Foreign Application Priority Data, "(EM)" should read -- (EU) --; and

Title page, item (57) CLAIM, "closing device" should read -- CLOSING DEVICE --.

Signed and Sealed this
Eighteenth Day of January, 2011

David J. Kappos
Director of the United States Patent and Trademark Office
